OIL BURNER

Julius J. Jorgensen, Detroit, Mich., assignor to
 Kelvinator Corporation, Detroit, Mich., a corporation of Michigan

Application December 31, 1932, Serial No. 649,699

5 Claims. (Cl. 158—77)

The present invention relates to oil burners and more particularly to oil burners for household heating plants.

One of the objects of the present invention is 5 to provide a rotating fuel distributing well to deliver the fuel from the well to the point of mixture with the air by radially extending fuel feed channels.

Another object of the invention is to arrange 10 fan blades alongside of the fuel feed channels for causing the air to be distributed equally at the points of outlet of the fuel feeding channels.

Other and further objects and advantages will 15 be apparent from the following disclosure, reference being had to the accompanying drawings wherein a preferred form of embodiment of the present invention is clearly shown:

In the drawings:

Figure 1 is a side view of the improved burner, 20 parts thereof being shown in longitudinal cross section;

Fig. 2 is a sectional view taken on line 2—2 of Fig. 3 and showing the rotary fuel feeding mechanism removed from the oil burner casing;

25 Fig. 3 is a side view of said mechanism looking in the direction of arrows on line 3—3 of Fig. 2;

Fig. 4 is a view partly in section, the section being taken on line 4—4 of Fig. 3.

Referring to the drawings, there is shown a base 30 which is supported for swinging movement on a post 21. This post may be carried by any suitable bracket not shown. The base 20 supports an electric motor 23 which drives a shaft 24. Formed integrally with the base 20 is a cylindrical 35 casing 25, the left end of which is provided with a flange 26. A sheet of fire-resisting material such as asbestos 27 is attached to the right of the flange 26 by screws 28. The casing 25 is intended to be inserted into the fire box of a furnace 40 and preferably through the fuel feeding door opening therein and the asbestos 27 is arranged to close this opening in the furnace. The inner end of the casing 25 is flared outwardly as at 30 and an annular band 31 of sheet metal is secured at 45 this end of the casing 25 by screws 32. This band carries therein a heating ring 34. This heating ring is carried by the screws 35 and the diameter thereof is slightly less than the interior diameter of the band 31 so as to leave a space as at 36. A disc 31 is carried at the end of the casing 25 by screws 38 and is provided with a series of reverse bends so as to form a groove 39 for the screws 38 and form a housing 40. A gas pipe (not shown) is connected with the interior of the 50 housing 40 and the disc is provided with a series of small orifices 41 for the escape of the gas between the band 31 and the ring 34. This gas, when lighted, will cause the heating of the ring 34 for preheating purposes.

60 A frame 42 is disposed within the casing 25

and held in position by screws 43. This frame 42 provides two bearing supports, one of which is shown at 45 for journaling the shaft 46. This shaft 46 is driven by the motor shaft 24. The inner end of the frame 42 is flared outwardly as at 48 and the upper end of this flare 48 carries a tube type nozzle 49. Fuel is supplied to the nozzle 49 from a casing 50 by a pipe 51. The fuel may be conveyed to the casing 50 and the quantity of fuel delivered thereto may be controlled in any 10 suitable manner. Preferably, the quantity of fuel delivered thereto is controlled by a room thermostat (not shown).

Referring particularly to Fig. 2, it will be noted that the shaft 46 is hollow and a spider 54 is connected therewith by screw threaded engagement. In the present instance, this spider is provided with three legs 55. A member 57 is driven by the spider 54. The member includes a disc-shaped ring 56. Ring 56 is connected at the extreme ends 20 of the legs 55 of spider 54 by rivets 58. At the inner portion of the ring 56 the member 57 is provided with a series of reverse bends to provide a circular-shaped well 60. From the well 60, the member 57 merges into a frusto conically shaped 25 portion 61 and a cylindrical portion 62. The outer end of the cylindrical portion 62 is guided by three posts 63. These posts are riveted to the shaft 46, there being openings 64 in the shaft in which a riveting tool may be inserted. The 30 outer ends of these posts slidably and frictionally engage the interior of the cylindrical portion 62 so as to maintain said portion in its proper position while permitting longitudinal expansion thereof. Extending outwardly from the well 60 35 is a series of tubes 66 and in the present embodiment, three of these tubes 66 are shown. It will be noted that the tubes 66 are spaced a slight distance from the disc-shaped ring 56. Holes 67 are provided in the well in alignment with the tubes 40 66 so that fuel may flow from the well 60 into the tubes 66.

Bosses 70 are provided on the spider legs 55 and carry a saucer shaped disc 71, held in place by screws 72. Two sheet metal bells 74 and 75 are 45 spaced from one another as at 76 and the flange portions thereof are secured to the disc 71 by screws 77. A sheet of asbestos 79 lies flat alongside the disc 71 and is interposed between the bell 74 and the disc 71 and is held in place by 50 being clamped between the disc 74 and the disc 71.

A plurality of fan blades 80 are suitably secured to the disc 71 and extend toward the ring 56. It will be noted in Fig. 4 that the tubes 66 extend between these fan blades.

Since the spider 54 is carried by the rotating shaft 46, it will cause rotation of the ring 56, distributing well 60, conically shaped member 61, discs 71, 74 and 75 and likewise the fan blades 80. 60

It will be noted that the nozzle 49 extends to within a short distance of the conically shaped member 61, whereby the rotating conical member 61 will wipe the fuel off of the nozzle 49. This fuel will travel outwardly on the conically shaped member 61 due to centrifugal force and enter the well 60, whence it will flow through the tubes 66 and will be sprayed in the form of vapor against the interior of the hot ring 34.

10 Air for supporting combustion of the vapor, which is thrown by centrifugal force from the outer ends of the tubes 66, is supplied by a fan 85 driven by the shaft 24. An opening 85 is provided in the frame 42 for permitting the air 15 to flow from the interior of the casing to the interior of the frame, whence it is delivered to the interior of the cylindrical portion 62. This air is then forced between the disc-shaped ring 56 and the disc 71. I have found that by providing 20 a plurality of fan blades 89 interposed between the discs 56 and 71, that a uniform discharge of air is maintained over the entire circumference of the ring 56 and disc 71. Also, the air is directed over the tubes 66 and toward 25 the ring 34 in the proper manner and thereby maintains a uniform flow of air about all the tubes to insure uniform atomization of the fuel and thereby insure a uniform ring of combustion.

A damper 88 is provided at the opening 85 in 30 the frame 42 for the purpose of controlling the quantity of air delivered and this damper may be controlled thermostatically or in any suitable manner.

On the upper end of the casing 25 are formed 35 bosses 89 which carry a shroud 90 which substantially surrounds the upper half of the casing 25 and forms a passage 92. The inner end of the casing 25 is open at 93 to the interior of the passage 92 and an opening 94 is arranged in the bracket 26. The purpose of the passage 92 and the openings 93 and 94 is to permit air, which is forced by the fan 85 through the casing 25, to flow 40 over the moving parts, within the interior of the casing, and escape through the opening 94 to the exterior of the furnace whereby to cool the working parts within the hot furnace.

I have found that by providing tubes 66 as herein shown, and by causing a uniform distribution of air that substantially no carbon deposits 50 on the ring 34 nor within the tubes 66. The space between the bell discs 74 and 75 and the asbestos 73 maintains a relatively high differential in temperature between the exterior of the bell 75 and the disc 71. However, due to the fact that 55 the disc 71 is within the interior of the furnace and subject to the heat thereof, there is a tendency for the same to buckle, due to expansion. In order to prevent such buckling as would distort the same, I have provided two series of slots 60 96 and 97. There are three slots in each of these series, and the slots in series 96 are staggered with respect to the slots in series 97. This arrangement permits a large expansion and contraction of the disc 71 without causing the same 65 to buckle out of shape.

While the form of embodiment of the present invention as herein disclosed constitutes a preferred form, it is to be understood that other forms might be adopted, all coming within the 70 scope of the claims which follow.

What I claim as my invention is:

1. In a fuel burner for a heating system, the combination with a rotatable frusto conically shaped fuel delivering means, of a rotatable fuel distributing well lying radially outwardly of said fuel delivering means and in fuel receiving relation with the exterior surface of said means, rotatable means providing radially extending fuel feeding channels communicating with the distributing well for receiving fuel therefrom and for distributing such fuel radially, means for rotating 10 said elements, and means for feeding fuel to the exterior surface of the fuel delivering means. 5

2. In a fuel burner for a heating system, the combination with a rotatable frusto-conically shaped fuel delivering means, of a rotatable fuel 15 distributing well lying radially outwardly of said fuel delivering means and in fuel receiving relation with the exterior surface of said means, rotatable means providing a plurality of radially extending fuel feed tubes communicating with the 20 distributing well for receiving fuel therefrom and for distributing such fuel radially, means for rotating said elements, and means for feeding fuel to the exterior surface of the fuel delivering means. 25

3. In a fuel burner for a heating system, the combination with a rotatable frusto conically shaped fuel delivering means, of a rotatable disc-shaped ring forming a fuel distributing well, said well lying radially outwardly of said fuel delivering means and in fuel receiving relation with the exterior surface of said means, a plurality of radially extending tubes carried by and adjacent the disc-shaped ring in fuel receiving relation with the well for receiving fuel therefrom and for distributing such fuel radially, means for rotating 30 said elements, means for feeding fuel to the exterior surface of the fuel delivering means, and means for forcing air for combustion alongside the disc-shaped ring about the tubes. 40

4. In a fuel burner for a heating system, the combination of a rotatable fuel feeding member comprising a substantially frusto conically shaped portion having a fuel distributing well formed around the edge of its larger end in fuel receiving 45 relation with the exterior surface of said conically shaped portion, said member also comprising a disc shaped ring extending radially from said well; means for rotating said member; means for feeding fuel to the exterior surface of the fuel 50 feeding member; and a plurality of tubes connected with the well and receiving fuel therefrom, said tubes extending alongside said disc-shaped ring, and means for forcing air for combustion alongside the disc-shaped ring about the 55 tubes.

5. In a fuel burner for a heating system, the combination with a rotatable frusto conically shaped fuel feeding means, of a rotatable fuel distributing well lying radially outwardly of the base 60 of said fuel feeding means and in fuel receiving relation with the exterior surface of said means, rotatable means providing radially extending fuel feeding channels communicating with the distributing well for receiving fuel therefrom and 65 for distributing such fuel radially, means for rotating said elements, and adjacent means directed toward the exterior surface of said frusto conically shaped fuel feeding means for delivering fuel thereto. 70

JULIUS J. JORGENSEN.
